UNITED STATES PATENT OFFICE.

CHARLES A. BERTSCH, OF CAMBRIDGE CITY, INDIANA.

BENDING-ROLL.

SPECIFICATION forming part of Letters Patent No. 408,685, dated August 13, 1889.

Application filed May 4, 1889. Serial No. 309,628. (No model.)

To all whom it may concern:

Be it known that I, CHARLES A. BERTSCH, of Cambridge City, Wayne county, Indiana, have invented certain new and useful Improvements in Bending-Rolls, of which the following is a specification.

This invention relates to machines for bending sheet metal, &c. Such machines generally consist of a pair of rolls, which grip the metal and propel it forward over the third roll, which compels the metal to curl up out of its normal plane into a circle whose radius depends upon the adjusted position of the third roll. The two rolls which grip and propel the sheet will be herein designated the "pinching-rolls," while the third roll will be designated as the "bending-roll." Sometimes in machines of this class the rolls are disposed pyramidal—*that is to say*, there are two lower rolls on one level and an upper roll centrally over these two. In this case the rolls all coact as bending-rolls and pinching-rolls, the degree of curvature of the bending being adjusted by adjusting the distance which the lower periphery of the upper roll projects below the upper peripheries of the lower rolls.

In exemplifying my invention I have chosen to show two pinching-rolls and a bending-roll in the manner first indicated.

In bending-rolls sometimes the sheets or rings of metal are bent into complete circles, which can only be removed from the rolls by some endwise system of withdrawal. This is generally provided for by hinging one of the bearings of one of the pinching-rolls, so that this bearing can be removed, leaving the end of the roll clear for the withdrawal of the ring which has been bent. Such removable bearing I term a "buckle-bearing." The pinching-rolls having been properly adjusted to pinch the sheet, it becomes generally necessary to throw them out of such adjustment, in order to permit the rolled-up sheet or ring to be removed, and when a second sheet or ring is to be rolled a new accurate pinching adjustment is called for.

One object of my invention is to avoid the necessity for this accurate adjustment or for any disturbance of the accurately-pinching adjustment.

A further object is to provide for readily opening the rolls at the time of removing the buckle-bearing.

A further object is to cause one pinching-roll to counterbalance the weight of the other pinching-roll, in order that the opening of the rolls may be performed with ease.

The principle of my invention will be readily understood from the following description of an exemplification of it, taken in connection with the accompanying drawings, in which—

Figure 1 is a front elevation of a bending-machine, exemplifying my improvements; Fig. 2, an elevation, at the tail end thereof of the right hand of Fig. 1 being considered as the tail end of the machine and the left-hand end as the head of the machine; Fig. 3, an elevation of the right-hand face of the head-housing, various parts appearing in vertical section in plane of line *a* of Fig. 1; Fig. 4, an elevation, in the same plane as in Fig. 3, of the head-box of the lower pinching-roll with its immediate accessories; Fig. 5, a front elevation of the right-hand portion of the rolls, viewed as in Fig. 1, but with the tail-housing appearing in vertical section in the plane of line *b* of Fig. 2; Fig. 6, an elevation similar to Fig. 5, but showing the buckle-bearing as removed and the tail-housing in vertical section in the plane of line *c* of Fig. 2.

In the drawings, *A* indicates the head-housing; *B*, the tail-housing; *C*, the top pinching-roll; *D*, the lower pinching-roll; *E*, the bending-roll arranged for adjustment in the housings in the usual manner; *F*, the head-journal of the top pinching-roll, having its usual bearing in the head-housing and projecting outwardly beyond the same, as usual, for the reception of gearing, an outboard-bearing, &c.; *G*, the tail-bearing of the top pinching-roll; *H*, the usual gearing connecting the two pinching-rolls; *J*, wedges under the boxes of the lower pinching roll to serve as a means for vertically adjusting that roll to secure the desired pinch upon the sheet; *K*, the head-box of the lower pinching-roll, vertically adjustable in the head-housing and adjusted therein for the desired pinch by means of its proper wedge; *L*, the tail-box of the lower pinching-roll, similarly arranged and similarly adjusted in the tail-housing; *M*, a movable support under the head-box *K*, this movable support taking the form, in the exemplification, of a block adapted to slide vertically in the housing, this block forming the abutment on which the appropriate wedge

acts; N, an outboard-bearing upon the journal F; O, a lever disposed along under the rolls and journaled to the head-housing and projecting therefrom to the tail-housing, and projecting, 5 also, outwardly beyond the head-housing, this lever engaging under the block M; P, a link connecting the outboard-bearing with the lever O, where the lever projects beyond the head-housing; Q, the usual hand-screws for 10 operating the wedges; R, the tail-journal of the lower pinching-roll; S, the buckle-bearing hinged to the tail-housing and engaging the tail-journal of the top pinching-roll, and adapted to be swung out of engagement with 15 that journal, as indicated in Fig. 6; T, the pivot on which the buckle-bearing swings; U, a crank on the tail-journal of the lower pinching-roll, to serve in turning the pinching-roll by hand; V, a vertical slot through the buckle- 20 bearing to permit the swinging of the buckle-bearing past the crank; W, a removable pin engaging the tail-housing and the buckle-bearing when the buckle-bearing is in normal position, this pin serving as a latchingment 25 for holding the buckle-bearing in normal position and for permitting the buckle-bearing to be swung out of normal position; X, an opening-lever fulcrumed upon the pivot of the buckle-bearing and normally standing up- 30 right contiguous to the buckle-bearing; Y, a cam upon the lower end of this opening-lever, engaging under the lever O, and serving, when the opening-lever is properly manipulated, to elevate the tail end of the lever O; Z, a 35 lock-lug upon the opening-lever, engaging over the tail end of the lever O, when the parts are in normal position; a in Fig. 1, the section-plane of Figs. 3 and 4; b in Fig. 2, the section-plane of Fig. 5; c in Fig. 2, the 40 section-plane of Fig. 6; d, a removable pin engaging the opening-lever X and the buckle-bearing and serving as a latchingment by which these two parts may be integrated or segregated, and e an adjustable weighted lever 45 formed at the top of the buckle-bearing.

In bending a sheet or bar these rolls operate in the ordinary manner and are adjusted in the ordinary manner, my improved construction presenting no features of novelty 50 in this respect.

When a sheet or bar has been bent into a ring upon the top roll and it is desired to remove the ring from the roll, the latchingment W is disengaged and the buckle-bearing swung 55 out of engagement with the tail-bearing of the top pinching-roll, thus leaving the tail end of the top pinching-roll clear, so as to permit the removal of the ring. This is as usual, my construction presenting no features 60 of novelty in this respect; but in ordinary construction, when the buckle-bearing has been swung clear, the wedges or other devices employed for effecting the pinching adjustment of the pinching-rolls would require to be manipulated in order to separate the pinching-roll, so as to permit the ring to be freely withdrawn, and before bending a new ring of

the same thickness and metal a readjustment of these devices would be called for. In the illustrated machine exemplifying my improvements the rolls are opened without disturbing the pinch-adjusting devices. Assuming that the buckle-bearing has been turned down into the position indicated in Fig. 6 implies that the latch-pin d has been disengaged, so as to 75 permit the buckle-bearing to swing down and leave the opening-lever X in normal position. The opening-lever is now turned down and the cam at its foot prys up the tail end of the lever O. This pulls down the outboard-bearing N and elevates the top opening-roll and to a certain extent opens the rolls; but this certain extent might not be sufficient on very wide sheets, owing to the fact that the head end of the top roll rises but very little, 80 the head-housing forming the fulcrum on which the top roll pivots, so to speak. It is to be understood, of course, that the tail-bearing of the top pinching-roll is to have clearance, so as to permit this tilting of the top roll. 85 This clearance may be given by depressing the lower surface of the bearing or by giving the bearing the form of a vertical ellipse, as indicated in the drawings. This detracts, of course, from the bearing-surface under the 90 journal; but when the machine is under the strains of work the strains are all met at the top bearing-surface, which needs no clearance. 95

In order to increase the amount of the roll-opening movement, I consider it advisable to 100 lower the head end of the lower pinching-roll simultaneous with the raising of the top pinching-roll. This I accomplish in the exemplification by supporting the wedge of the head box of the lower pinching-roll by means of 105 the lever O, so that the same motion of the lever O which tilts the top pinching-roll to the opening position will permit the head end of the lower pinching-roll to descend. The tail end of the lower pinch-roll is not disturbed, but simply tips a little in its box. 110 Now it will also be apparent that this principle of construction not only secures an advantageous opening of the rolls, but also that the weight of the head end of the lower pinching-roll counterbalances to a certain extent the weight of the upper roll. Therefore the attendant in operating the opening-lever to 115 elevate the top roll finds the weight of the lower roll aiding him. Instead of disengaging 120 the latch-pin d and operating the buckle-bearing, and subsequently the opening-lever, the latch-pin d may be left in engagement, and then the mere act of swinging the buckle-bearing down will serve to open the rolls. 125 Not only is this the case, but the weight of the heavy buckle-bearing then becomes an element in the counterbalancing system, the weight of the lower roll helping to counterbalance the buckle-bearing, and vice versa. 130 The parts may in the process of construction be proportioned into such degree of counterbalancing as is desired, or the lower pinching-roll may be arranged for preponderance,

and the adjustable weight-lever *e* on the buckle-bearing be arranged to bring about the desired equalization. An advantage of this latter feature is that heavy rings being produced add their weight to the weight of the lower pinching-roll, and the adjustable weight *e* serves as a means by which this can be compensated for as the work progresses.

It will be understood that as the buckle-bearing moves outwardly it moves in the arc of a circle, and that, therefore, in order to clear its roll-journal the bearing-aperture must have the proper clearance below, similar to the head-bearing of the top roll. This is common practice, I believe, in buckle-bearing construction.

It is to be understood, of course, that the machine illustrated is a mere exemplification of my invention.

I have explained the principle of my invention and the best mode in which I have contemplated applying that principle, and I now proceed to particularly point out and distinctly claim that which is original with me and sought to be covered by Letters Patent.

It will be at once apparent that all of the merits of my invention are available in rolls in which but two rolls are used—such machines, for instance, as are employed in longitudinally-corrugating tubes and rings, in which machines the bending-roll is of course not needed. In practice I have employed my present invention in this class of machines, as well as in machines provided with the third roll for bending purposes.

I claim as my invention—

1. In bending-rolls, the combination, substantially as set forth, of a pair of housings, top and bottom pinching-rolls journaled therein, a removable buckle-bearing at the tail end of the top pinching-roll, an outboard-bearing at the head end of the pinching-roll, and mechanism connecting said buckle-bearing and outboard-bearing in such manner that the disengagement of the buckle-bearing will cause the depression of said outboard-bearing.

2. In bending-rolls, the combination, substantially as set forth, of a pair of housings, top and bottom pinching-rolls journaled therein, a buckle-bearing engaging the tail-journal of the top pinching-roll, a vertically-movable support for the head-bearing of the bottom pinching-roll, and mechanism connecting said buckle-bearing and supported in such manner that the disengagement of the buckle-bearing will permit the descent of said support.

3. In bending-rolls, the combination, substantially as set forth, of a pair of housings, top and bottom pinching-rolls journaled therein, a buckle-bearing engaging the tail-journal of the top pinching-roll, an outboard-bearing at the head end of the top pinching-roll, a vertically-movable support for the

head-bearing of the lower pinching-roll, and mechanism connecting said buckle-bearing and outboard-bearing and movably supported in such manner that the disengagement of the buckle-bearing causes the descent of said outboard-bearing and movable support.

4. In bending-rolls, the combination, substantially as set forth, of a pair of housings, top and bottom pinching-rolls journaled therein, a buckle-bearing engaging the tail-journal of the top pinching-roll, an outboard-bearing at the head of the top pinching-roll, a roll-opening lever, and mechanism connecting said lever with said outboard-bearing in such manner that the manipulation of said lever may serve in elevating and depressing said outboard-bearing.

5. In bending-rolls, the combination, substantially as set forth, of a pair of housings, top and bottom pinching-rolls journaled therein, a buckle-bearing engaging the tail-journal of the top pinching-roll, a vertically-movable support for the head-bearing of the lower pinching-roll, a roll-opening lever, and mechanism connecting said lever with said movable support in such manner that the manipulation of said lever produces vertical movement of said vertical support.

6. In bending-rolls, the combination, substantially as set forth, of a pair of housings, top and bottom pinching-rolls journaled therein, a buckle-bearing engaging the tail-journal of the top pinching-roll, an outboard-bearing at the head of the top pinching-roll, a vertically-movable support for the head-bearing of the lower pinching-roll, a roll-opening lever, and mechanism connecting said lever with said outboard-bearing and said movable support in such manner that the manipulation of the lever will elevate or depress said outboard-bearing and movable support.

7. In bending-rolls, the combination, substantially as set forth, of a pair of housings, top and bottom pinching-rolls journaled therein, a vertically-moving bearing for the head-journal of one of said pinching-rolls, a buckle-bearing engaging the tail-journal of the top pinching-roll, mechanism connecting said buckle-bearing with said vertically-moving bearing in such manner that the disengagement of the buckle-bearing causes a roll-opening movement of said vertical bearing, and an adjustable counterbalance-weight on said buckle-bearing.

8. In bending-rolls, the combination, substantially as set forth, of a pair of housings, top and bottom pinching-rolls journaled therein, a crank at the tail of the lower pinching-roll, and a buckle-bearing engaging the tail-journal of the top pinching roll and vertically slotted at said crank.
